AND ALFRED B. HALL, OF SAME PLACE.

Letters Patent No. 73,824, dated January 28, 1868.

IMPROVED FILE-CUTTING MACHINE.

The Schedule referred to in these Letters Patent and making part of the same.

TO ALL WHOM IT MAY CONCERN:

Be it known that I, JOHN B. MIGNAULT, of Boston, in the county of Suffolk, and State of Massachusetts, have invented certain Improvements in Machines for Cutting Files, of which the following is a full, clear, and exact description, reference being had to the accompanying drawings, making part of this specification, in which—

Figure 1 is a perspective view of the front of a file-cutting machine with my improvements applied thereto.
Figure 2 is a rear elevation of the same.

Figure 3, a vertical section on the line $x\ x$ of fig. 2.

Figure 4, a vertical section on the line $y\ y$ of fig. 2.

Figure 5, a vertical section on the line $z\ z$ of the same figure; and

Figure 6, a detail representing the cutter, with its spring-arm, and some of the mechanism for operating the same.

The process of cutting files by machinery, as heretofore constructed, has been attended with very unsatisfactory results, *i. e.*, it has been found impracticable to make every tooth of the same uniform height, and with as smooth an edge as can be produced by hand. Some of the difficulties to be overcome in order to obtain the desired result may be enumerated as follows, *viz*:

First. The density of the steel or metal of which the blank is composed is apt to vary at different points through its length, and where the cutter or chisel was rigid, and operated by uniform blows of a hammer, it was impossible to raise the roughened surface to a uniform level, as the indentations upon the soft places were much deeper than those upon the hard places, and a corresponding irregularity of tooth was the result.

Second. The blank is frequently wider from the tang to the centre than at its opposite end, and it is obvious that a given force, that will make the required indenture at the wider part of the file, will drive the cutter or chisel too deep at the narrower part or point of the file.

Third. The file-blank frequently tapers in thickness, as well as in width, and a further allowance or adjustment is required to prevent the hammer from falling through a greater distance when operating upon the thin than on the thick part of the blank.

Fourth. The workman, when cutting files by hand, adjusts his cutter, preparatory to each cut, by drawing it back against the burr or front of the tooth last cut; the straps he employs enabling him to perform the said office. With machinery, however, it is different, for while it is necessary that the file have a comparatively soft bed on which to rest for the protection of the teeth on one side, while the other side is being cut, it is equally necessary that this bed be unyielding, otherwise the action of the hammer and chisel upon its surface will vary at different points; and, in connection with the above requirements, there is another still more important, that the blank be held firmly and immovably upon its bed in order to properly receive the blow imparted by the hammer to the cutter, and to be accurately fed between the successive cuts.

My invention has for its object to overcome (as far as possible) the above-mentioned difficulties, and consists chiefly in pivoting the cutter or chisel loosely to a spring-arm, the cutter being so pressed by a spring as to throw its outer edge down upon the blank, while its inner edge is slightly raised above it, to be subsequently brought down by the elongation or increased leverage of the spring-arm resulting from its retracting power, whereby the chisel is made to adjust itself to the conformation of the surface of the blank before being struck by the hammer, the spring-arm enabling the chisel to yield while being struck, thus causing it to move in a manner similar to that when the operation of cutting is performed by hand.

My invention also consists in sliding the block to which the spring-arm carrying the cutter is attached within a slot in the framework, to allow of the various adjustments of the cutter necessary for producing any required inclination of cut; and my invention also consists in an adjustable sliding lever, provided with a screw for lifting the spring-arm to raise the chisel from off the blank while being fed forward.

To enable others skilled in the art to understand and use my invention, I will proceed to describe the manner in which I have carried it out.

In the said drawings, A is the bed, from which rise standards B in suitable bearings; in which revolves the shaft C, which is driven by power applied to the pulley D, a loose pulley, E, being provided for disconnecting the machinery from the power, when desired. The shaft C carries two cams, F G, (to be described hereafter,) and at one of its extremities a bevel-gear, H, which engages with a corresponding gear, I, on a short shaft, J, which turns in bearings K, the inner ends of which are screwed, at a, to the upper side of one of the standards B. One end of the shaft J projects outside one of its bearings, and carries a circular disk, L, having a dove-tailed groove, b, extending diametrically across it for the reception of a block, M, of corresponding form, to slide therein. To a stud projecting from this block M is secured one end of a long arm or connecting-rod, N, the other end of which is attached by a pin, e, to a crank, O, on one end of a horizontal screw-shaft, P, which has its bearings in the bed A, and passes through a projection on the under side of a table, Q, (see fig. 5.) Upon a raised portion of the bed A are formed dove-tailed ways d, upon which the under side of the table fits, the revolution of the screw-shaft causing it to slide back and forth thereon.

To the upper side of the table Q is secured, at e, a shield, R, the upper surface of which is made of soft metal to serve as a rest for the file-blank S, and to protect the teeth on one side from injury when the blank is turned over to form the teeth on its opposite side. The tang of the blank passes through an aperture in a block, f, which fits and moves vertically in a square slot cut in the shield, the lower end of the block being enlarged to prevent its removal from the upper side, the end of the tang resting in a cavity formed in a metal piece, g, screwed to the shield R, by which means (in connection with a wedge-shaped key, h, passing through the block f) the blank, when pressed down by the binder T, (presently to be described,) is prevented from moving laterally, while it is free to rise and fall slightly in a vertical direction to allow its lower surface, while being cut to rest snugly upon and fit the shield at the point immediately under the hammer and chisel, to properly receive the blow without being bent.

Secured to the table Q is a former, U, the shape of the upper surface of which corresponds exactly to that of the upper and lower sides of the blank to be cut. Upon this former rests a roll, i, which is free to revolve thereon when the table is moved back and forth, the roll turning upon a pin, j, which passes through the bifurcated ends of an arm, k, which is secured by a pin, l, immovably to a shaft, m, which rests in bearings in the side of the standards B.

n is a stiff spring, of the form shown in figs. 1 and 3, one end of which is screwed to a square projection, o, formed on the shaft m, the other end passing near to and directly under the heel or projection p, formed on the helve of the hammer V, and being provided with a hole, into which turns a screw-bolt, q, for the purpose of regulating the tension of the spring, and consequently the vibrations of the hammer, when operated by the revolution of the cam F.

r is a check-nut for retaining the spring in place after being adjusted. The hammer-helve is securely fixed to a shaft, s, which is pivoted on the conical ends of two spindles t, which are provided with screw-threads to allow the shaft s to move to one side or the other when the hammer requires to be adjusted over the chisel or cutter, the construction of which will now be explained.

Upon a pin, u, passing through an opening at one end of a spring-arm, W, is loosely pivoted a cutter, X, of the form seen, one side of the head of which, from 10 to 11, is made slightly rounding, and receives the blow of the hammer, the other side of its head being curved downward to the point 12, (see fig. 6.) Owing to the inclination of the cutter from the vertical, and that of its edge across the length of the blank, necessitated by the changes in the position of the spring-arm, the head of the cutter is made to one side of the centre, in order to insure the blow of the hammer being imparted directly to the centre of the blank. The inclination of the cutter with respect to the blank (horizontally and vertically) is the same as when the operation is performed by hand in order to throw up teeth of the required form.

Y is a bent spring for throwing the outer edge of the cutter down upon the blank, and at the same time lifting its inner edge slightly up therefrom, the pressure or retraction of the spring-arm downward serving subsequently to push the outer edge of the cutter along the blank, and bring the inner edge of the cutter down thereon, by which means the whole length of the cutter-edge is made to snugly embrace the blank in the direction required to be given the cut. The spring Y also prevents the cutter from vibrating too far; otherwise it would be liable to be struck before it had time to adjust itself to the face of the blank.

The tension or resistance of the spring-arm W serves to keep the cutter X constantly pressed down upon the blank until relieved periodically by mechanism (soon to be described) to allow of the feeding of the blank. The end of the spring-arm W, opposite to that in which the cutter is pivoted, is screwed, at 13, to a square metal block, Z, the lower end of which fits into and slides within a curved slot, 14, cut in the bed A, and when adjusted into the required position for making the cut desired, is securely held in place by tightening the screw-nut 15.

On the end of the shaft m opposite to that to which the "former" is secured, is loosely fitted a sleeve, v, terminating in a bent arm, w, to the portion 16 of which is secured a circular sleeve or roller, which is confined thereon by a washer and pin, (not shown,) and serves as a "binder," T, to press the blank (while being fed forward) down firmly on its shield at a point immediately in advance of the cutter.

The device employed for holding the "binder" down upon the blank while being cut, and for releasing it from the shield to remove or turn it over, will now be described.

20 is a bent spring, one end of which is secured, at 21, to the upper side of the sleeve v, the other end of the spring resting upon a cam or eccentric, 22, which is pivoted, at 23, to one of the standards B, and is operated by hand by means of its arm or lever 24. To a post or standard, 25, rising from the bed A, is pivoted, at 26, a bent lever, 27, of the form shown in section, fig. 4, the upper end of which rests against the cam G, by which it is operated. To the lower end of this lever 27 is secured, by means of a screw-bolt, 28, an arm, 29, provided with a slot, 30, through which the bolt 28 passes. One end of this arm is provided with a screw, 31, which may

be turned therein up against the under side of the spring-arm W, to throw the cutter up from off the blank after the stroke of the hammer, (see fig. 4.)

By the construction above described, the length of the leverage of this arm may be increased or diminished to bring the screw 31 under and support it at all times during the various positions occupied by the block Z within its slot 14.

The number of teeth, and the space between them, are regulated by the following mechanism: 32 is a toothed wheel or ratchet secured to the horizontal screw-shaft P, and is turned by the vibration of the crank O, which also operates a retaining-pawl, 33, which is prevented from being thrown up out of contact with the wheel by means of a coiled spring, 34, the length of the throw of the connecting-rod N being increased or diminished by sliding its block M farther from or toward the centre of the disk L, thus causing the pawl to drop into a greater or less number of teeth, according as the file is to be coarser or finer.

35 is a stiff bent spring carrying a rubber block or cushion, 36, to prevent the hammer from recoiling too far to strike the cutter the second time to form one tooth.

Operation.

The blank being fitted to its shield, and its tang wedged in place within the block f, the table is moved until the "point" 37 of the blank is brought under the cutter, which, in making the first or "over" cut, occupies (with its arm and block) the positions shown in red, fig. 1, the cutter being so placed that the upper portion, 10 to 11, of its head is reversed, that is, it is removed farther from the axis of the sliding block Z than shown in section, fig. 6, this being the only position in which the cutter will impart the blow directly to the centre of the blank.

The slotted arm 29 is now slid in till its screw 31 is brought under the spring-arm W and turned up against it, so that it may raise the cutter while the blank is feeding.

After the tension of the hammer-spring n is regulated, and the adjustments of the connecting-rod N made to conform to the fineness of file required, the binder T is pressed down upon the blank, (rolling over its upper surface immediately in advance of the cutter,) and the power is applied to the driving-shaft.

The motion of the table A causes the "former" U to travel under the guide-roll i, which is thus raised and lowered, thereby increasing or diminishing the resistance of the spring n, and consequently regulating the force of the hammer and depth of the tooth made by the cutter to those portions of the blank corresponding in shape to those of the "former" U. The cutter being loosely pivoted, its edge is free to swing or rock upon the blank till it snugly and fairly rests upon its surface, when the hammer is raised by the cam F pressing on its heel or projection, p, after which the cam is liberated therefrom, and the resistance of the spring n throws it down upon the head of the cutter.

As the shaft continues to revolve, the cam G strikes the upper end of the bent lever 27, pressing it outward, and at the same time throwing up the slotted arm 29, and causing the screw 31 to lift the spring-arm W to raise the cutter X from off the blank, which is now fed forward, the binder T rolling freely over its upper surface and holding the portion of the blank under the cutter firmly upon its shield while being struck, the block f allowing the blank to adapt itself snugly and truly thereto.

After the blank is fed, (when one tooth has been cut,) the end of the slotted arm 29 is depressed by the action of the cam G on the upper-end of the bent lever 27, and the screw 31 is carried down below the spring-arm W, the resistance of which, on being liberated, causes the cutter X again to adapt itself to the blank, in a manner previously explained.

After one row of teeth has been cut, the power is disconnected by throwing the belt upon the loose pulley E, and the table is turned back by revolving the screw-shaft P into its original position. The block Z is now slid in its slot 14 to the position seen in black, fig. 1, and the cutter being reversed in its spring-arm W, the blank is ready to receive the second or cross-cut. After the two rows of teeth have been cut on one side of the blank, and the feed of the table is discontinued, by lifting the pawl 33 out of contact with the ratchet 32, the wedge h is driven out of the block f, and the blank removed and turned over, to be again secured therein to receive similar cross-rows of teeth on its other side.

It is evident that the shape and position of the spring Y, as well as the material of which it is made, may be changed; for instance, it may be a spiral or rubber spring, and be placed at the back of the head of the cutter, and any other device for effecting the same end may be employed instead of the spring Y. The mechanism may also be so multiplied as to cut a number of files at one operation, without departing from the spirit of my invention.

It will be seen from the foregoing description that when a cutter is employed, in connection with a spring or flexible arm, W, and spring, Y, the operation of cutting the teeth can be performed in a manner entirely satisfactory, as the motion and position of the cutter are similar to those given by hand.

Claims.

What I claim as my invention, and desire to secure by Letters Patent, is—

1. I claim a cutter, X, pivoted loosely to a spring-arm, W, in combination with a spring, Y, substantially as and for the purpose set forth.

2. I also claim the combination of the adjustable block Z, cutter X, and bed R, substantially as and for the purpose set forth.

3. I also claim the lever 27, with its slotted arm 29, in combination with the adjustable screw 31, or its equivalent, substantially as and for the purpose described.
